CLAIM

The ornamental design for a universal bracket assembly, as shown and described.

DESCRIPTION

FIG. 1 is a perspective view of a universal bracket assembly of the present invention having a first bracket element in an assembled condition;

FIG. 2 is a top plan view of the universal bracket assembly and the first bracket element;

FIG. 3 is a bottom plan view of the universal bracket assembly and the first bracket element;

FIG. 4 is a rear elevation view of the universal bracket assembly and the first bracket element; the front elevation view being a mirror thereof;

FIG. 5 is a right side elevation of the universal bracket assembly and the first bracket element; the left side elevation view being a mirror thereof;

FIG. 6 is a perspective view of the universal bracket assembly comprising first and fourth bracket elements; and,

(Continued)

FIG. 7 is a bottom view of the universal bracket assembly comprising first and fourth bracket elements.
